CLAIM

The ornamental design for a shoe sole, as shown and described.

DESCRIPTION

FIG. 1 is a perspective view of a portion of a shoe sole showing my new design embedded in an insole or sole of the shoe;

FIG. 2 is a partial, enlarged perspective view thereof; FIG. 3 is a partial, enlarged top plan view thereof; and, FIG. 4 is an enlarged cross-section view thereof taken along line 4-4 of FIG. 3 thereof.

The broken lines shown in the drawings show unclaimed subject matter as well as the boundaries of the areas of enlargement. The broken lines and subject matter they depict form no part of the claimed design.
